TOBACCO CUTTING MACHINE

Patrick Quintin Robert Schreiber, London, England, assignor to Robert Legg Limited, London, England

Application April 11, 1935, Serial No. 15,881
In Great Britain April 19, 1934

5 Claims. (Cl. 146—109)

This invention relates to improvements in rotary tobacco cutting machines.

The main object of the invention is to provide a rotary tobacco cutting machine which has a high output of cut tobacco in a given time with a relatively low speed of advance of the knife edge through the mass of the tobacco.

In the rotary machines, in order that a high output of cut tobacco may be obtained, the arm carrying the knife must revolve at a relatively high speed, which means that the speed at which the knife strikes the mass of the tobacco as it issues from the mouthpiece is so high that a satisfactory, regular, clean cut is not obtained for which reason rotary machines have not to date found much favour. To obviate this it has been proposed to employ a cutter having a number of knives, mounted on a series of arms or a cutter in the form of a disc, which is rotated at a much slower speed. Even so, the speed of the knife through the tobacco is still higher than with the reciprocating type of cutter and in the case of a disc cutter it is necessary to provide mechanisms of a complicated nature for moving the cutter to and away from the mouthpiece.

My invention consists broadly in employing a knife or cutter with a spiral cutting edge. This construction of knife enables me to retain the advantages of a rotary motion with the added advantage of a relatively slow cutting speed and a very marked shearing and slicing action.

The form of the spiral is dependent upon the size of the mouthpiece through which the tobacco is fed, the advance of the spiral being equal to the depth of tobacco to be cut. The knife may consist of a spirally shaped blade mounted between two plates forming the holder; which is preferably so arranged that the blade has a dished appearance when in position whereby only the cutting or bevelled edge is in contact with the tobacco "cheese". The plates may be of spider construction to ensure lightness.

The axis of the knife is arranged centrally of the mouthpiece and in use the inside edge of the spiral is arranged to coincide substantially with the top edge of the mouthpiece so that as the knife revolves the spiral edge of the knife advances relatively slowly across the shallow depth of the mouth through the mass of the tobacco until at the end of a complete revolution the spiral edge will have passed over the complete surface of the mouthpiece and a slice of tobacco cut off. The inside edge of the spiral knife then commences another cut.

It will readily be seen that although the speed

of the surface of the knife across the tobacco is high, the cutting edge advances through the mass of the tobacco relatively slowly, and as the direction in which it advances is the depth of the mouth, which is always less than the width, a very slow cutting speed is obtained.

The knife may be revolved at a relatively high speed, and the cutting speed will still be less than with the reciprocating type of machine.

Another object is to provide means for automatically advancing the cutter or knife to take up wear as it rotates.

A further object is to provide a means for grinding and thus sharpening the knife blade or blades when the machine is in operation and also for truing up the grinding wheel.

The invention is illustrated in the accompanying drawings in which Figure 1 is a sectional elevation extending lengthwise of the machine, and Figures 2 and 3 respectively an end and plan view thereof.

Figure 4 is a detail view looking from the rear in the direction of the arrow of Figure 1.

Figure 5 is a front view of the cutter.

Figures 6 and 7 are fellow detail views. 25

The accompanying drawings illustrate a tobacco cutting machine in which A indicates generally the bed or framework of the machine and B the sides of the feed trough into which the tobacco to be cut is fed. Extending along the bottom of the trough is an endless feed band C mounted on a pair of front rollers D and rollers E and F, the foremost front roller D being the driving roller and the rear roller F a tensioning roller.

At the front end of the feed band C the tobacco 35 passes under the large top compression roller G and is then fed forward on to an endless flexible metal band H and beneath a series of three compression rollers J1, J2, J3. The band H is mounted on support rollers K and straining and driving rollers respectively indicated at L and K1. The straining roller L is mounted in two eccentric bushes in the side frames of the machine. The two rear top rollers J2, J3 are mounted in a pair of sub-frames M which frames are pivotally supported to rock about the axis of the top front roller J1. The mounting for the top front roller J1 is formed in a pair of brass side frames N which as is hereinafter described are automatically adjustable and guided vertically with respect to the 40 bed of the machine.

To each of the sub-frames M are pivotally attached links O whose lower ends are pivoted to weighted levers P pivotally carried by the side frames of the machine. These weighted levers P 45

revolution will effect a displacement of the arm 38 and thus cause the ratchet wheel 40 to be advanced a predetermined amount through the pawl 39.

8 Fast on the shaft 41 is a pinion 42 that meshes with a larger pinion 43 on the end of a feed screw 44 by means of which the grinding wheel is advanced.

It will be appreciated therefore that while 10 the machine is running, tobacco is being fed by means of belts C and H and the associated rollers through the mouthpiece R where it will meet the cutting knife. At the same time that part of the knife not in action is being ground, the grinding 15 wheel is being dressed at intervals and also fed forward by the amount that has been dressed off, whilst the knife is also being drawn back continuously towards the mouthpiece to compensate for the amount that is ground off by 20 the grinding wheel.

Referring to Figure 1 the grinding wheel 24 is mounted to rotate within a chamber 45 formed within the bridge piece, an aperture 46, which is of a size greater than the wheel 24 so as to provide an annular opening therearound, being formed in the front wall of the chamber. In the top wall of the chamber 45 is a port 47 connected through a pipe 48 to a suction fan 49. Particles of steel and grinding material are thus drawn 30 through the opening by the action of the fan 49 which blows them into a dust collector 50 at the side of the machine.

The collector 50 consists of a fabric filter which is removable and for this purpose is held at its 35 top end by a clip 51 to the fan connection and at its bottom end by means of another clip 53 which secures it around a cup 52, supported on a bracket 54.

The machine may be driven either by a belt 40 from an overhead shaft or as is shown by a motor 55 from which drive is transmitted through a belt connection 56 to a shaft 57 which enters the gear case 23. From this gear case is obtained the drive to the endless metal band H, the feed band C, the top rollers J1, J2, J3 and G and to the knife spindle 9, the knife feed shaft 20, the grinding wheel dressing shaft 28, the shaft 25 for the grinding wheel and to the suction fan 49 through the belt drive 58 and also to an oil pump 50 which supplies oil to all the working parts in the gear box.

Control of the machine is obtained by two 55 clutches operated by levers 59 and 60. The lever 59 operates the clutch which disengages the knife from the driving shaft 57 while the lever 60 disengages the feed gear driving the endless band H, the top rollers J1—J3 and G and the feed band C.

By operating these clutch levers independently 60 it is possible either to revolve the knife independently of the feed or to drive the feed independently of the knife, or it is possible to have the driving shaft 57 revolving without either the feed or the knife being driven.

65 At the side of the gear box is mounted a movable cover 61 within which are a pair of gear wheels mounted on two counter-shafts (not shown). By changing these gear wheels the relation of the advance of the feed to the revolutions 70 of the knife may be altered so that the machine may be adjusted so as to give any number of cuts required per inch of the material fed.

Attached to the front of the machine is an annular guard casing 62 which surrounds the knife 75 and is provided at its lower side opposite the

mouthpiece with a discharge opening indicated generally at 63.

Beneath this opening is a feed chute 64 down which the cut tobacco discharges by gravity and thence it may be collected on a conveyor (not 5 shown) or a container. The front of the casing 62 is enclosed by a glass panel held in place by a retaining ring 66, the front of the casing being hinged at 67 so that it may be opened in order to remove or inspect the knife. 68 is a securing 10 latch.

What I claim is:—

1. In a rotary tobacco cutting machine, the combination of a main frame, a mouthpiece, a feed trough carried by said main frame for feeding tobacco to be cut through said mouthpiece, a bridge piece mounted on the main frame transversely over said trough and above said mouthpiece, a housing slidably carried on said bridge piece for movement longitudinally of the trough, 15 bearings on said housing, a shaft mounted to rotate in said bearings and projecting from said housing longitudinally of the trough, a cutter fast on the shaft and having a knife with a spirally shaped edge which is set to rotate in a 20 plane so that the knife edge advances across the mouthpiece, means for rotating the shaft and cutter, grinding means adjustably mounted on said bridge piece diametrically opposite to and above the mouthpiece, which grinding means is 30 adapted to contact with the knife edge as it rotates, and means for automatically adjusting the housing in order to compensate for wear of the knife.

2. In a rotary tobacco cutting machine, the 35 combination of a main frame, a mouthpiece, a feed trough carried by said main frame for feeding tobacco to be cut through said mouthpiece, a bridge piece mounted on the main frame transversely over said trough and above said mouthpiece, a housing slidably carried on said bridge piece for movement longitudinally of the trough, 40 bearings on said housing, a shaft mounted to rotate in said bearings and projecting from said housing longitudinally of the trough, a cutter 45 having a spirally shaped edge fixed on the shaft and so positioned that the edge advances across the mouthpiece, means for rotating the shaft and cutter, a second housing adjustably carried by the bridge piece, a grinding wheel mounted to 50 revolve in said second housing, the plane of rotation of the grinding wheel being substantially coincident with the plane of the mouthpiece, means mounted adjacent the grinding wheel for truing up the grinding wheel during rotation 55 thereof, and means for moving the cutter housing towards the mouthpiece and for moving the second housing toward the cutter for the purpose specified.

3. A machine as claimed in claim 2 including 60 a cam shaft rotatably mounted on the bridge piece, an arm fast on the shaft and provided with a diamond member adapted to contact the grinding wheel for truing up the latter, a cam on the shaft, means for rotating the cam shaft, an arm 65 pivotally mounted on the bridge piece and in operative engagement with said cam, pawl and ratchet mechanism operatively connected to said second housing for moving the latter toward the cutter, and means operatively connecting said 70 arm with said pawl and ratchet mechanism.

4. A tobacco cutting machine as defined in claim 1 including a movable upper mouthpiece edge, the means for feeding the tobacco to be cut to the mouthpiece including a travelling bed, 75

- 5 a series of pressure rollers, and side plates movable vertically relatively to the machine frame, which side plates support at least one of the pressure rollers and have attached to them the movable edge of the mouthpiece, the throw of the spirally shaped cutting edge being sufficient to enable the knife to advance across the mouthpiece even when the mouthpiece is displaced.

5. A cutter as claimed in claim 2 comprising a knife in strip form and in which the cutter includes a back plate and a gripper plate having spirally extending edges with bevelled faces set at an angle to the axis of the cutter and between which faces the knife strip is mounted.

PATRICK QUINTIN ROBERT SCHREIBER.
